UNITED STATES PATENT OFFICE.

PAUL HARIVEAU, OF PARIS, FRANCE.

CENTRIFUGAL PUMP.

Application filed August 2, 1920. Serial No. 400,784.

To all whom it may concern:

Be it known that I, PAUL HARIVEAU, a citizen of the Republic of France, residing at Paris, France, have invented certain new and useful Improvements in Centrifugal Pumps, of which the following is a specification.

This invention relates to single and multiple disc centrifugal pumps and is characterized by the fact that each element is composed of an end plate forming one side of the intake passage; of a crown ring fitted with guide vanes, which completes the intake passage; by a volute suction chamber, a rotor and a volute delivery chamber; each of these different members forming separate castings, and the volute intake chamber being assembled with the end plate on the one hand and the volute delivery chamber on the other; the elements being grouped together by means of a bracing crown ring.

In the accompanying drawing, which illustrates, by way of example, several methods of carrying out the invention, Figure 1 is a vertical section of a single disc pump, composed of one element, with a single-intake rotor. Figure 2 is a similar view of a single disc pump composed of one element with double-intake rotor. Figure 3 is a similar view of a duplex pump, composed of two elements each with a single-intake rotor. Figure 4 is a duplex pump, composed of two elements each with a double-intake rotor. Figure 5 is a modification of Figure 4.

Referring to the drawing in detail the end plate 1 is provided with two extensions, the outer one, 2, carrying the cap 3, whilst the inner one, 4 is intended to guide the fluid as far as the intake 5 of the rotor 6, which is preferably keyed on the shaft 7 by means of a key 8, which is provided, at the ends of the hub, with two recesses 9 and 10, in which engage two flexible split rings 11 and 12. The crown ring 13 provided with guide vanes 14, bounds the chamber of the rotor 6, and forms, with the end plate 1, the intake passage 15. This crown ring 13 is secured to the end plate 1 by means, for example, of threaded bolts embedded in the thickness of the vanes 14. Around the intake passage 15 is arranged an intake volute 16 with a flange 17 for connecting to the suction pipe. 18 is the delivery volute, with flange 19; and 20 is the removable cover plate of the pump. The shaft 7, supported on a friction reducing bearing 21 mounted in a cap 22, is prefer-

ably provided with a bush 23 partially spaced from the end plate 1 to provide a chamber 27 and having a shoulder 24. The shaft is also provided with a collar 25 having a shoulder 26 and a chamber 28, the respective chambers 27 and 28 being in communication with the chamber of the rotor 6, by means of pressure tubes 29 and 30 respectively, with the object of dispensing with stuffing boxes. Water under pressure issuing from the pump through the tube 30 enters the circular groove 28 and is then divided, the greater part returning to the chamber of the rotor, passing between the ring 25 and the shaft 7, the remainder of water passing out in the opposite direction between the ring 25 and the shaft 7. The water thus enters the chamber 53 and escapes through the outlet orifice 55. The movement of the water from the groove 28 to the chamber 53 prevents the admission of air at the point where the shaft passes out through the pump. The crown ring 13 is provided with a groove, not shown, intended to house a cord or metallic segments to make tight joints. Feet 31 and 32 serve as supports.

This centrifugal pump is preferably assembled in the following order. The cover plate 20 is assembled, in succession, with the volute 18 and foot 32, and the driving shaft 7, on which the rotor 6 has previously been keyed, being inserted through the cover plate 20, the intake volute 16 is assembled with the delivery volute 18. The crown ring 13, provided with the guide vanes 14, and secured to the end plate 1, is then placed in position. The end plate 1 is finally assembled with the intake volute 16 and the foot 31.

The chief advantages of the centrifugal pump according to the invention are the following:

1. The pump may be inspected and dismounted without touching the intake and delivery pipes. To facilitate taking down, the end plate 1 is provided with disconnecting screws, not shewn, bearing against the intake volute 16, and enabling the end plate 1, crown ring 13 (with the guide vanes 14), rotor 6 and shaft 7 to be detached in one piece.

2. The intake and delivery orifices may occupy any desired relative positions, and that, too, independently of each other.

3. The rotor is fed uniformly, as the result of the long course traversed by the fluid

from the guide vanes 14 to the intake 5 of the rotor 6.

4. The possibility of varying the delivery within very wide limits. To obtain these 5 variations, all that is necessary is merely to replace the delivery volute 18 and rotor 6 by other sets of volutes and rotors, this being practicable because the space between the crown ring 13 and the cover plate 20 is determined 10 by the external distance between the two lateral flanges of the volute 18.

5. The casting and machining of the various parts of the pump are a very simple matter.

15 6. The parts liable to wear can be replaced and the other retained.

The single disc centrifugal pump represented in Figure 2, which consists of one element with a double-intake rotor is obtained, according to the invention, by arranging the different parts of Figure 1—minus the cover plate 20—symmetrically in relation to a double-intake rotor.

This pump is assembled in a manner similar 25 to that of Figure 1.

In addition to the advantages mentioned in connection with Figure 1, this modification includes that of abolishing all axial thrust, and consequently that of obtaining 30 perfect axial equilibrium.

Figure 3 shows that the constituent members of an element with single-intake rotor (Figure 1 minus the cover plate 20), enable a duplex-rotor centrifugal pump, with single intake, to be put together very simply. To arrive at this result, all that is necessary 35 is to assemble with the pump according to Figure 1 (the cover plate 20 of which has been removed), a symmetrical element that 40 is to say composed of the same members as those in Figure 1, but arranged in reverse order, and to connect the delivery orifice of the delivery volute 18 to the intake orifice of the intake volute 16¹. The chambers of the 45 two rotors are bounded by a crown ring 35, which is centered and maintained in the desired position, preferably by means of three screws (not shown), which are operated from the outside and engage with their ends 50 in a groove provided in the crown ring 35.

The back flow of water from one chamber towards the other, or towards the intake, is prevented by means of cords or metal segments, forming joints, housed in suitable 55 grooves provided in the crown rings 13 and 35.

This modification presents the advantage that, when the pump is working, the effects produced by the two rotors are supplementary, as regards the delivery head of the fluid, whilst, from the fact that they are arranged back to back, the axial thrust exerted on the rotor 6 is almost completely balanced by that acting on the rotor 36, and 60 consequently, axial equilibrium is nearly 65

achieved even in the case of two single-intake rotors.

Figure 4 shows how, by starting from the pump illustrated in Figure 2, that is to say, one element with a double-intake rotor, it is 70 easy to obtain centrifugal pumps with double-intake rotors, irrespective of the number of rotors desired. In fact, all that is necessary is to add a similar group to the one represented in Figure 2, and to assemble 75 them by means of a bracing crown ring 40. Inside this bracing crown ring 40 is disposed another crown ring 41, preferably provided, right and left, with a base forming one of the sides of the adjacent intake 80 passage. The centering of the crown rings 13 and 41 is effected in the manner already described. The reflex of water is also prevented as set forth.

In this modification, the delivery volute 85 18 is connected to a central header, not shewn, supplying the two intake volutes 42 and 43. Moreover, as in the pump shown in Figure 2, complete axial equilibrium is obtained.

Figure 5 is a modification of Figure 4, in which the crown rings 13 are cast with a peripheral ridge 44 which engages in a recess arranged at the junction of the corresponding volutes. These joints, which are 90 lined with a circular packing, prevent the fluid from leaking from the one element into the adjacent one and towards the intake and, at the same time, they keep the crown rings centered. The ridges might be extended advantageously to form flanges intercalated between the volutes and assembled therewith. Moreover, the crown rings 40 and 41 (Figure 4) are preferably 95 replaced by a single crown ring 45.

The assembling and taking down of this pump (Figure 5) are evidently effected in separate portions.

The forms given by way of example are confined to duplex pumps with single—or 110 double-intake rotors; but it is evidently feasible to construct pumps comprising any desired number of elements, by simply adding to those of Figures 3, 4 or 5, and in the manner indicated, as many single disc elements (Figures 1 and 2) as required.

The invention thus enables the delivery head to be increased without increasing the volume delivered, or, on the other hand, the delivery to be increased without increasing the head. The delivery head is increased by connecting (series mounting) the mouth of the first delivery volute with the intake of the next element in succession, by an external branch. On the other hand, the delivery 125 is increased by connecting the mouths of all the intake volutes with the same headers, and connecting all the mouths of the delivery volutes to another header (parallel mounting). In this way a pump of very 130

large capacity can be obtained, with rotors of very small diameter, which enables high speeds to be employed.

This possibility of grouping the elements 6 in order to increase the delivery head or volume delivered, enables all intermediate forms of grouping to be arranged, for instance, arranging half the elements in parallel and the other half in series. Again, if 10 the delivery or head exceed the desired limits, the number of elements worked may be cut down to the desired figure.

The invention is applicable not only to centrifugal pumps for liquid, but also to 15 fans, and more particularly to hydraulic turbines of small capacity and large head. If the elements composing the turbine are connected in series the speed will be the lower for a given head, as the number of 20 elements will be greater, since they each take a share of said head. If grouped in parallel, they will each take a share of the volume. This has resulted in the employment of 25 rotors of small diameter run at very high speed. Should the available volume of the fall diminish, one or more elements can be cut out, so that the others continue to act under the conditions most favourable to efficiency.

30 What I claim is:

1. A centrifugal pump comprising a cover plate forming one side of the intake passage, a crown ring provided with guide vanes which completes the intake passage, an intake volute, a rotor and a delivery volute, each of these different parts being cast separately, means to assemble the intake volute with the cover plate on one hand and the delivery volute on the other.

40 2. A centrifugal pump comprising a plurality of elements, each element including a cover plate forming one side of the intake passage, a crown ring provided with guide vanes which completes the intake passage, an intake volute, a rotor and a delivery volute, each of these different parts being cast separately, means to assemble the intake volute with the cover plate on one hand and the delivery volute on the other, and a bracing crown ring interposed between each two elements.

50 3. A centrifugal pump comprising a plurality of elements, each element including a cover plate forming one side of the intake passage, a crown ring provided with guide vanes which completes the intake passage, circular ridges formed on said crown ring bedded in recesses provided in the volutes and forming tight joints, an intake 55 volute, a rotor and a delivery volute, each of these different parts being cast separately; means to assemble the intake volute with the cover plate on one hand and the delivery volute on the other and a bracing crown ring interposed between each two elements.

4. A centrifugal pump comprising a plurality of elements, each element including a cover plate forming one side of the intake passage, a crown ring provided with 70 guide vanes which completes the intake passage, circular ridges formed on said crown ring bedded in recesses provided in the volutes and forming tight joints, an intake volute, a rotor and a delivery volute, each of these different parts being cast separately; means to assemble the intake volute with the cover plate on one hand and the delivery volute on the other and a bracing crown ring interposed between each two elements; a ball bearing supporting the shaft and a cap mounted on the extension of one of the pump covers and carrying the shaft, a bush and a ring surrounded by water under pressure.

5. A centrifugal pump comprising a cover plate forming one side of the intake passage, a crown ring provided with guide vanes which completes the intake passage, an intake volute, a rotor provided with a hub, a delivery volute, each of these different parts being cast separately, means to assemble the intake volute with the cover plate on one hand and the delivery volute on the other, a socket forming extension of the cover plate and surrounding the 85 pump shaft and the hub of the rotor.

6. A centrifugal pump comprising a plurality of elements, each element including a cover plate forming one side of the intake passage, a crown ring provided with 100 guide vanes which completes the intake passage, an intake volute, a rotor and a delivery volute, each of these different parts being cast separately, means to assemble the intake volute with the cover plate on one hand and the delivery volute on the other, and a bracing crown ring interposed between each two elements; a socket forming extension of the cover plate and surrounding the pump shaft and the hub of the rotor.

7. A centrifugal pump comprising a plurality of elements, each element including a cover plate forming one side of the intake passage, a crown ring provided with guide vanes which completes the intake passage, circular ridges formed on said crown ring bedded in recesses provided in the volutes and forming tight joints, an intake volute, a rotor and a delivery volute, each of these different parts being cast separately; means to assemble the intake volute with the cover plate on one hand and the delivery volute on the other and a bracing crown ring interposed between each two elements, a socket forming extension of the cover plate and surrounding the pump shaft and the hub of the rotor.

8. A centrifugal pump comprising a cover plate forming one side of the intake passage, an intake volute, a rotor, a delivery 130

volute, the cover plate, intake volute, rotor and delivery volute being cast separately, and means to assemble the intake and delivery volute and the cover plate.

6 9. A centrifugal pump comprising a cover plate forming one side of the intake passage, an intake volute, a rotor arranged at one side of the cover plate, a delivery volute, the cover plate, intake volute, rotor 10 and delivery volute being cast separately, means arranged at the opposite side of the rotor forming an enclosure therefor, and means to assemble the intake delivery volute and the cover plate.

15 10. In a centrifugal pump, a cover plate

forming one side of the intake passage, a rotor provided with a hub, and a socket forming extension on the cover plate partially receiving the pump shaft and hub of the rotor.

11. In a centrifugal pump, a cover plate forming one side of the intake passage, a rotor provided with a hub, a shaft supporting said rotor, and a socket forming extension carried by the cover plate receiving the 25 shaft and hub and arranged to direct incoming fluid against the rotor.

In testimony whereof I affix my signature.

PAUL HARIVEAU.
